Attorney

UNITED STATES PATENT OFFICE.

JOHN O. GADBERRY, OF JOPLIN, MISSOURI.

SOCKET WRENCH.

Application filed August 10, 1922. Serial No. 580,941.

To all whom it may concern:

Be it known that I, JOHN O. GADBERRY, a citizen of the United States, residing at Joplin, in the county of Jasper and State 5 of Missouri, have invented certain new and useful Improvements in Socket Wrenches, of which the following is a specification.

This invention relates to wrenches, and more particularly to socket wrenches.

10 In the present invention, I provide a socket wrench having a plurality of interchangeable sockets, and means for retaining the sockets in position on the handle.

15 The retaining means consists of a squared portion on the handle, adapted to be received in a squared portion of the socket and a spring to retain the socket in position, to permit removal when desired.

20 In the present construction, I provide a spring consisting of a portion extending over the squared end of the handle and having V-shaped ends projecting beyond the sides of the handle.

25 An object of the invention is the provision of a wrench of this character, which will be simple in construction, and cheap to manufacture.

30 A further object is the provision of a wrench having interchangeable sockets which may be readily removed and replaced.

In the accompanying drawings, I have shown one embodiment of the invention. In this showing:

Figure 1 is a side elevation,

35 Figure 2 is a similar view on an enlarged scale, parts being shown in section,

Figure 3 is an end elevation of a number of interchangeable sockets,

40 Figure 4 is a transverse sectional view on line 4—4 of Figure 2,

Figure 5 is an end elevation of the handle with the socket in position,

Figure 6 is a transverse sectional view on line 6—6 of Figure 2, and,

45 Figure 7 is a perspective view of one end of the wrench showing the socket removed.

Referring to the drawings, the reference numeral 1 designates the handle which is provided with a brace portion 2 having an end 3 arranged in alinement with the main portion of the handle. The lower end of the handle is provided with a slightly enlarged portion 4 and a squared end 5. A

retaining member is arranged on a squared end. As shown, the retaining member consists of a piece of resilient metal having a base portion 6, extending across the squared end and secured thereto by a screw 7. The ends of the retaining member project beyond the sides of the squared portion, as at 8, and are then extended inwardly, as at 9, the angular portions 8 and 9 forming a substantially V-shaped member. As shown, the angular portion 8 is connected to the base by a portion 10, arranged at right angles to the base portion and substantially in alinement with the sides of the squared end. A plurality of sockets are provided, the sockets having openings of different sizes and being adapted to be arranged on the squared portion of the handle.

In Figure 3 of the drawings, I have shown a set of sockets 11. Each of the sockets consists of a central portion 12 having a squared opening 13 of substantially the same diameter as the squared portion of the handle and provided with end portions 14 which are shown hexagonal in shape, adapted to receive hexagonal nuts or bolt heads. It is, of course, apparent that the ends of the socket members may be shaped as desired. As shown, in Figure 2 of the drawings, the two ends of each socket are provided with different sized openings, whereby two sized wrenches may be obtained for each socket.

A socket member is adapted to be arranged on the opposite end of the handle portion, free to rotate thereon, forming a hand grip. The handle member 15 is substantially similar in construction to the socket members 11, and is provided with a sloping outer surface 16. This member is provided with hexagonal openings 17 at each end, and a squared intermediate opening 18 to permit it to be used as a socket member when desired. The end 3 of the brace or handle is provided with an enlargement 19, adapted to engage the shoulder formed between the squared portion of the opening and one of the socket portions to limit the inward movement of the handle member. This end of the handle is provided with a retaining member 6, identical in construction with the retaining member heretofore described and adapted to operate in the same manner.

The operation of the device will be ap-

parent from the foregoing description. When a socket member is to be placed on the handle, it is forced inwardly, riding over the inclined portions 9 of the retaining member, to the position shown in the drawings. When in this position, the socket member is retained on the handle with sufficient force to prevent accidental displacement. The squared portion 5 of the handle received in the squared opening 13 of the socket member, causes the socket member to revolve with the handle when the handle is operated. When the socket member is to be removed, the application of slight pressure thereto causes it to ride over the inclined portion 8 of the retaining member. By providing the substantially V-shaped terminals to the retaining member, the socket member is guided on and off the handle, compressing the ends of the retaining member and permitting the socket member to pass over the projecting portions thereof.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A socket wrench comprising a handle having a reduced squared end, a socket member having a reduced squared opening for the reception of the reduced end of the handle, and a resilient member having its intermediate portion arranged on the squared end of the handle, said member being extended laterally from said intermediate portion beyond the sides of the squared portion of the handle, and being then extended outwardly.

2. A socket wrench comprising a handle having a squared end, a socket member having a squared opening therein, and a resilient retaining member having a base arranged on the squared end of the handle and a pair of end portions projecting beyond the squared end of the handle, each of said end portions consisting of a pair of inclined sections forming a substantially V-shaped spring.

In testimony whereof, I affix my signature in presence of two witnesses.

JOHN O. GADBERRY.

Witnesses:

W. O. HANKS,
ZORA THOMPSON.
